UNITED STATES PATENT OFFICE.

AUGUSTE SANDOZ, OF NEUCHATEL, SWITZERLAND.

STEM-WINDING WATCH.

SPECIFICATION forming part of Letters Patent No. 326,677, dated September 22, 1885.

Application filed May 18, 1885. (No model.)

To all whom it may concern:

Be it known that I, AUGUSTE SANDOZ, director of the watch-maker school of Neuchatel, Switzerland, have invented a new and useful 5 Improvement in Stem-Winding Watches, of which the following is a specification.

My invention relates to a stem-winding mechanism of great simplicity and of much greater strength than the devices heretofore 10 in use. Its working is very reliable.

In the accompanying drawings, Figure 1 shows a plan view of my stem-winding mechanism with section through *x y*, and Fig. 2 a section through *U W* of the same.

15 The stem *D* is retained in the pendant by means of a screw, *a*, and its pivot *d* turns in the bridge *E*. On a squared part of the stem *D* slides a pinion, *C*, with click-teeth. The barrel *B* of the watch is placed in such a 20 manner as to bring the beveled or click-toothed wheel *A*, fixed on the arbor of the barrel, in gear with the pinion *C*, also provided with click-teeth. A spring, *F*, fixed to the bridge *E* by means of screws *f f*, presses 25 the pinion *C* against wheel *A*, and allows the same to work as a click when the stem is turned backward. A click, *I*, acted upon by a spring, *J*, prevents the arbor of the barrel 30 *B* turning backward under the influence of the mainspring. The wheel *A* being of a

large size and the gear of the click-teeth being very strong, the winding up of the watch by means of pinion *C* and wheel *A* is very reliable. If turned backward, the pinion works as a click, as already mentioned.

Having thus described my invention, what I claim is—

The combination, with the barrel *B*, its shaft and spring, of the wheel *A*, secured to said shaft and having inclined teeth, a spring-click 40 to keep the wheel *A* and barrel from turning backward, the winding-stem *D* and crown, the click-pinion *C*, fitted to slide on a squared portion of said stem and having teeth inclined in the opposite direction to those of the wheel *A*, 45 and the spring *F*, for keeping the pinion *C* in gear with the wheel *A*, whereby when the stem and pinion are turned in one direction the wheel *A* is revolved and the spring wound up, and when turned in the other direction the 50 pinion rides over the teeth of *A* without turning said wheel *A*, substantially as and for the purposes set forth.

Signed by me this 29th day of April, A. D. 1885.

AUGUSTE SANDOZ. [L. S.]
